UNITED STATES PATENT OFFICE.

EDMUND F. CAMPBELL, OF VANCOUVER, BRITISH COLUMBIA, CANADA.

GLARE-PREVENTING DEVICE FOR AUTOMOBILE HEADLIGHTS.

Application filed November 28, 1923. Serial No. 677,486.

To all whom it may concern:

Be it known that I, EDMUND F. CAMPBELL, citizen of the Dominion of Canada, residing at Vancouver, in the Province of British Columbia, Canada, have invented certain new and useful Improvements in Glare-Preventing Devices for Automobile Headlights, of which the following is a specification.

This invention relates to a means preventing the glare from an automobile headlight reflector.

Many devices have been adopted for reducing the glare from a headlight reflector or for dimming the light, but all such with which I am acquainted are either ineffective or depend on a diminution of the light to an extent as to render it practically useless for illumination of the roadway.

The device, which is the subject of this application, is designed to prevent the light of the lamp being reflected forward from the back or smaller curvature of the parabolic reflector in common use with such lights, without lessening in any way the full outward projection of the light.

The invention is particularly described in the following specification, reference being made to the drawings by which it is accompanied, in which:

Fig. 1 is a vertical section of the lamp and its reflector in the casing protecting the same, showing the application of the shield which is the particular subject of this application.

Fig. 2 is a sectional elevation of the shield to an enlarged scale, and

Fig. 3, a face view of the same.

In these drawings 2 represents the bulb of the lamp, removably connected to its socket 3, and 4 is the parabolic reflector, through the back end of which the lamp socket 3 is projected. 5 is the casing in which the lamp and its reflector are suitably supported and 6 is the glass through which the light is projected forward from the reflector.

Between the socket 3 and the lamp bulb 2 is introduced a shield 8, preferably a segment of a sphere with non-reflecting surfaces. This shield 8 is held up to the lamp bulb 2 by a spring 10 between the reflector 4 and the shield 8 with a washer 9 of as-

bestos or the like heat resisting material between the shield and the lamp bulb.

The effect of this shield is to cut off the light of the lamp 2 from the back end or smaller curvature of the reflector 4, permitting the light to fall only on the outer zone of the reflector.

At close range the light from the lamp being reflected from the outer zone shows a central dark space, but at a further range the light rays, converging slightly, prevent this dark central portion from being seen as such.

The effect of this device in preventing glare is very marked, and the result is attained without any sensible diminution of the light as reflected forward. I attribute this result solely to the light not being allowed to fall on the inner end of the reflector.

I do not desire to be confined to the particular form of shield here set forth as the same may be a circular disc or the after part of the lamp bulb 2 may be coated with an opaque non-reflecting material, the substance of the invention being the introduction of a light obstructing screen between the back of the lamp bulb and the after part of the parabolic reflector.

The device is exceedingly simple and has the further advantage that it is readily applicable to all existing lamps without any requirement of change in existing parts.

Having now particularly described my invention, I hereby declare that what I claim as new and desire to be protected in by Letters Patent, is:

A glare preventing means for a reflecting headlight which comprises the combination with a lamp and its reflector and the lamp socket projecting through the reflector, of a symmetrical shield of opaque material having a non-reflecting surface exposed to the light of the lamp and comprising a cup-like member apertured to permit passage of the base of the lamp, a heat resisting washer interposed between the shield and lamp bulb, and a coil spring interposed between the shield and reflector and encircling the socket, substantially as shown and described.

In testimony whereof I affix my signature.

EDMUND F. CAMPBELL.
